DESIGN FOR A LIGHTING FIXTURE

Edward B. Kirk, New York, N. Y., assignor to David Shapiro, New York, N. Y.

Application January 20, 1939, Serial No. 82,477

Term of patent 14 years

To all whom it may concern:

Be it known that I, Edward B. Kirk, a citizen of the United States, residing at New York, New York, have invented a new, original, and ornamental Design for a Lighting Fixture, of which the following is a specification, reference being had to the accompanying drawing, which forms a part thereof, in which:

Fig. 1 is a view in elevation of a lighting fixture embodying my new design; and

Fig. 2 is a plan view of the same fixture as it would appear from the bottom.

I claim:

The ornamental design for a lighting fixture, substantially as shown.

EDWARD B. KIRK.
